UNITED STATES PATENT OFFICE.

JOHN DOMAGOLA, OF PERU, ILLINOIS.

PAINTER'S BRUSH WIPER AND HOLDER.

SPECIFICATION forming part of Letters Patent No. 731,289, dated June 16, 1903.

Application filed September 26, 1901. Serial No. 76,715. (No model.)

To all whom it may concern:

Be it known that I, JOHN DOMAGOLA, a citizen of the United States, residing at Peru, in the county of LaSalle and State of Illinois, 55 have invented certain new and useful Improvements in Painters' Brush Wipers and Holders; and I do hereby declare the following to be a full, clear, and exact description of the invention, such as will enable others skilled in the art to which it appertains to make and use the same.

My invention is a device for the use of house, sign, and other painters for wiping surplus paint off from the brush after dipping in the 15 pail of paint and before applying to the work. This object is attained by using the device as hereinafter described.

Referring to the drawings, Figure 1 is a painter's pail with device in position. Fig. 2 20 is a top view of same. Fig. 3 is the device inverted, with a part of bracket-clamp broken away. Fig. 4 is a view of the edge of the device farthest from the center of the pail, showing the jaws for holding the brush-handle, but 25 omitting the bracket-clamp.

Fig. 1 is a painter's pail (such as are in general use) in a vertical position, with the top part of one side broken away to show the device in position and means for clamping the 30 same firmly to side of pail. Said device consists of a plate 1, a bracket-clamp 2, a thumb-screw 3, and jaws 4 for holding the brush-handle when the same is temporarily out of use, allowing paint to drip from brush back 35 into the pail.

Fig. 2 is a plan view of device, which stands a little above the pail, with the front or curved edge slightly lower than the back, causing all paint to drip into the pail instead of over 40 it. Jaws for holding the brush-handle are shown at 44, while 5 is a crescent-shaped slot which is cut in the plate 1 and the blank left adhering to the plate at ends near the center at 10 10—that is to say, the cut is made through 45 the plate corresponding to the curved front edge of the same. Said cut is made only at the sides and about one-third the way across each end from each side at 10 10, thus leaving one-third of the blank at each end uncut. 50 The blank is then bent down, as at 5 in Fig.

1, to make a point for the paint to drip from through the plate back into the pail. 6 is the front edge of the plate, cut slightly curved to fit the brush. When wiping the brush, it is desirable to wipe it more thoroughly at the 55 edge, and to accomplish this it follows that the front edge of the plate should be curved, or it would require two movements to wipe one side of the brush. 7 7 are rivet-heads to hold the spring-jaws from dropping through 60 the slots 8 8, in which they run, said jaws being wider on the under side of the plate than the upper parts, which work through slots in plate. Said jaws are drawn together by a spring 9, Fig. 4, and are kept from coming too 65 close together by the front of the jaws reaching the end of the slot at 13, Figs. 2 and 4.

Fig. 3 is an inverted view of the plate 1, with a part of the bracket or clamp 2 broken off, which bracket or clamp may be fastened 70 to the plate by any suitable means. 4 4 in Fig. 3 show the under side of the jaws for holding the brush-handle and the method of fastening rivets 77 in the jaws; also, the spring 9, which holds the jaws together. 75

Fig. 4 shows a back view of the plate 1 and the shape in which the upper part of the jaws are bent. To put the brush-handle in the jaws, press it down between in the opening at the top, which separates the jaws. 7 7 are 80 rivets in the jaws 4 4 and hold them in position, at the same time allowing the jaws to slide in the slots 8 8, Fig. 2. The spring 9, Figs. 3 and 4, draws the jaws together on the handle, thus holding the brush secure while 85 temporarily out of use.

Having thus described my invention, what I claim as new, and desire to secure by Letters Patent, is—

1. In a painter's brush wiper and holder, a 90 plate with a bracket or clamp having a slot cut near the forward or inner edge of the plate through the same, and having the ends of the blank left adhering and the sides bent down at an angle of about thirty degrees substantially as shown for the purposes set forth. 95

2. In a painter's brush wiper and holder a plate with a bracket-clamp and having its front or inner edge curved as shown for the 100 purposes described.

3. In a painter's brush wiper and holder a slotted plate with a bracket-clamp and having jaws for holding brush-handles said jaws working in the slots in the plate and drawn together with a spring substantially as described and for the purpose set forth.

5 In testimony whereof I have signed my

name to this specification in the presence of two subscribing witnesses.

JOHN DOMAGOLA.
